TANDEM MILL

Irving H. Tolles, Waterbury, Conn., assignor to
 The Waterbury Farrel Foundry and Machine
 Company, Waterbury, Conn., a corporation of
 Connecticut

Application December 18, 1933, Serial No. 702,929

9 Claims. (Cl. 80—36)

This invention relates to a new and improved tandem mill designed to reduce the cross sectional area of a piece of stock, such as a wire, rod, billet or the like, by successive compression operations.

It is the object of this invention, among other things, to produce a mill of this character wherein in a piece of stock, irrespective of its cross sectional shape, may be reduced to a predetermined cross sectional area by passes through successive pairs of rolls and at a speed greater than is possible under the present practice; to reduce stock having an initially larger cross sectional area than heretofore has been possible; and to increase the capacity of the mill by providing means whereby stock of varying initial cross sectional areas may be passed therethrough; as well as to produce a mill having the above and other characteristics and capable of producing a finished product of higher grade than heretofore possible, at an increased speed and at a minimum cost.

To these, and other ends, this invention consists in the tandem mill having certain details of construction and combinations of parts, as will be hereinafter described and more particularly pointed out in the claims.

In the conventional type of tandem mill new sets of rolls are installed for each size stock. Taking out the old rolls and installing proper sized new rolls requires much skill, and during the operation the mill is idle. The cost and maintenance of many rolls of various sizes is objectionable.

Again, the roll journals develop much heat and cause an expansion and distortion of the rolls and a corresponding variation in the diameter thereof. Such changes affect the thickness and shape, and therefore, the area of the stock passing therebetween. This change in area in turn affects the speed of the stock where such change occurs, and it no longer synchronizes with the speed of the rest of the mill, thus causing excessive slipping of the rolls on the stock or buckling of the stock.

These and other objections to the tandem mills, now in common use, are not present in the instant invention, wherein the roll journals have anti-friction bearings and the rolls a plurality of grooves in the face thereof, which in each of a series of rolls are adjustable into a common or work line, so that without taking down the rolls and substituting new ones therefor, stock having different initial cross sectional areas may be operated upon. The rolls are provided with anti-

friction bearings of such nature and construction as to practically eliminate the development of frictional heat sufficient to affect the diameter of the rolls.

The advantageous feature of the invention will appear from the following description and the accompanying drawings, which disclose for illustration only one form in which the invention may be applied.

Referring to the drawings, in which like numerals of reference indicate like parts in the several figures:

Figure 1 is a side elevation of a tandem mill embodying the invention herein;

Figure 2 is an enlarged cross section thereof, taken generally upon line 2—2 of Figure 1;

Figure 3 is an elevation looking in the direction of the arrows in Figure 2;

Figures 4, 5, and 6 are diagrammatic views illustrating various positions of the rolls relative to the work line; and

Figure 7 is a view of a wire or rod illustrating the various changes in its size as it passes through the rolls, each variation in area being the result of application of pressure thereto by one pair of 25 the series of rolls.

In the drawings, 10 indicates the machine bed that is supported upon suitable legs 11, with a motor 12 attached to the bed to provide a source of power for the drive shafts 13, through any convenient connection.

Mounted in the journal members 10' of the bed 10 at a right angle to each other, and inclined relatively to both a vertical and a horizontal plane, are a plurality of shafts 14, each having a drive gear 15 fixed thereon at its inner end. These shafts are spaced along the bed 10 in predetermined positions, and upon each shaft are suitable anti-friction bearings 16, 17, and 18, to properly take care of radial and thrust loads. The bearings 18 are held in spaced relation to each other by a spacer ring 19 in member 10'. Secured to the bed, adjacent to the upper end of the shafts 14, is a fixed retaining plate 20, within which is a filler ring 21 that is free to rotate 45 within the plate and also with the shaft.

Preferably fixed on the hub of the drive gear 15 is a relatively wide face pinion 22.

Adjacent to each shaft are the housings 23, in the base of which is threaded a screw 24, which is 50 rotatable in and held against endwise movement by the fixed plate 25. These housings are so mounted upon the bed 10 as to be moved thereon between the ways 48 substantially parallel with the axis of the shaft 14, and each housing is ad- 55

justable in a path at substantially a right angle to the next adjacent housing. Upon opposite sides of the housings 23 are the bearing housings 26, in each pair of which a roll is mounted, these rolls being designated 27 and 28. Upon each of these rolls are fixed the bearing rings 29, inside the race rings 30, and therebetween are the conical bearing rolls 31, arranged at an angle to the axis of the rolls 27 and 28, and at an angle to each other. The bearing rings 29 are held against outward movement by the filler rings 32, assisted in the case of the roll 28 by the nut 33. The race rings 30 are held against outward movement by a fixed retaining plate 34. Any other form or combination of anti-friction bearings that will take care of radial and thrust loads may be substituted for the form herein shown, if desired.

On each of the rolls 27 and 28 are the pinions 35, the teeth of which mesh into each other, and whereby the roll 28 is driven from the roll 27. Upon the roll 27 a gear 36 is fixed, the teeth of which mesh into those of the pinion 22. The widths of the faces of the pinion 22 and gear 36 are such that there may be a relative axial movement therebetween while retaining the intermeshing engagement of the teeth.

The rolls 27 and 28 are maintained in proper relation to each other by means of the screws 37 in the housings, which engage the bearing housings 26, or a bearing plate therebetween, if desired, and may be rotated synchronously from a shaft 38 having a pinion 39 therein, which meshes into the gears 40.

A graduated disk 41 fixed on one of the screws 37 with a finger 42 fixed relatively thereto, provides convenient means for an exact adjustment of the rolls toward and away from each other. As disclosed, each roll is provided with three grooves, severally designated 43, 44, and 45, which are of varying depth and shape as may be desired.

In the tandem mill there is a common work line, in which the stock always travels, irrespective of the groove in which it may be in contact. This work line is at the intersection of the lines A—A and B—B, and remains constant, and the several grooves are brought into register therewith. In Figures 2 and 4 the grooves 44 of the several rolls are in the work line.

In Figure 5 the rolls have been adjusted through the movement of the housings by the screw 24, so that the grooves 43 are in register with the work line.

In Figure 6, by a similar movement, the grooves 45 are brought into register with the work line. The wire or rod enters the machine at the left (Figure 1), and as it successively passes through each of the series of rolls, its cross sectional area is reduced. The rod illustrated in Figure 7 is one that has been removed from the rolls before completion of pass and after its area has been reduced by each of the successive pairs of rolls. The portion 46 at one end being the finished cross sectional area and the other end 47 the area as it approaches the first set of rolls. Thus, with the tandem mill shown herein having each roll provided with three grooves and with six pairs of rolls, it is possible to obtain eighteen area reductions upon one and the same wire or rod. The adjustment of the rolls relative to the shaft 14 is permissible by reason of the fact that the teeth on the gear 36 slide axially in those of the pinion 22. Each pair of rolls delivers the wire or rod at a higher lineal speed than the previous pair of rolls and the increase lengthening of the stock is accommodated by relatively higher speeds of the

rolls in the series, this higher speed corresponding in inverse ratio to the area of the wire delivered.

Suitable guards 50 conceal some of the gears and are added merely as a safety device.

The motive power is controlled by the operator at any point along the bed of the machine by the shipper rod 49 which operates in a well known manner.

This invention is not limited to any specific construction, arrangement or form of the parts, as it is capable of numerous modifications and changes without departing from the spirit of the claims.

What is claimed is:

1. In a tandem mill, a bed having substantially parallel side walls, one upon each side of the longitudinal center of the mill; a plurality of relatively short driven shafts journaled in the upper end of each of said side walls at an angle thereto, whereby the said shafts incline downwardly and inwardly and at their inner ends are spaced from each other, shaft means in the space between said walls located below the respective driven shafts and extending longitudinally of the bed, means to drive all of the driven shafts from said shaft means, a plurality of housings movably mounted upon the top of each side wall and spaced from each other in parallel relation, means connected with the bed for independently moving each housing toward and away from the said longitudinal center of the bed, a roll housing mounted within each of said housings, a pair of rolls journaled in each roll housing, and means to operate the rolls from the driven shafts in various positions relative to the drive shafts.

2. A mill for rolling material, having a bed formed with spaced sides and a top that has a pair of faces that incline downwardly and inwardly from the said sides, which sides and tops enclose an open space, with an opening between the inner lower ends of said tops, a plurality of driven shafts journaled in the underside of said tops, shaft means in said open space substantially parallel with and between the said outer sides and below the driven shafts; means within said open space to actuate the driven shafts from the shaft means, housings on the upper side of each face which correspondingly incline downwardly and inwardly, rolls journaled in the housings which also incline downwardly and inwardly and substantially parallel with and spaced from the adjacent driven shafts, means for moving the housings toward and away from each other upon said top faces, and means in part within said open space to operate the rolls from the driven shafts, bearing rings upon the journals of the rolls having oppositely disposed flared portions which incline toward the journals, race rings exteriorly of the bearing rings having correspondingly flaring faces, and roller bearings engaged with the respective flaring faces, and which incline at their outer ends toward the roll journals, and means to drive the rolls, there being at least one pair of roller bearing devices for each roll and whereby the development of frictional heat is practically eliminated that would otherwise control the diameters of the rolls through temperature variation.

3. A mill for rolling material, having a bed formed with spaced sides and a top that has a pair of faces that incline downwardly and inwardly from the said sides, housings on the upper side of each face which correspondingly incline downwardly and inwardly, rolls journaled in the housings which also incline downwardly and in-

wardly, bearing rings upon the journals of the rolls having oppositely disposed flared portions which incline toward the journals, race rings exteriorly of the bearing rings having correspondingly flaring faces, and roller bearings engaged with the respective flaring faces, and which incline at their outer ends toward the roll journals, and means to drive the rolls comprising in part a shaft for each set of rolls that is substantially parallel with and spaced therefrom and of approximately the same length, there being at least one pair of roller bearing devices for each roll and whereby the development of frictional heat is practically eliminated that would otherwise control the diameters of the rolls through temperature variation.

4. In a tandem mill, a bed having substantially parallel side walls, one upon each side of the longitudinal center of the mill and the top of the each wall being formed with an inwardly and downwardly inclined portion that is substantially flat upon its outer surface and terminates adjacent to and spaced from the inner end of the similar portion upon the opposite wall, and a plurality of journal members substantially parallel with said flat surfaces and each other that are spaced from each other lengthwise of the mill and positioned between the side wall and the underside of said inwardly and downwardly inclined portions; a plurality of driven shafts, substantially parallel with each other, that incline inwardly and downwardly from the side walls, one of these shafts being mounted in each of said journal members; shaft means in the space between the side walls and below the driven shafts that extend longitudinally of the bed; means to actuate the driven shafts from the shaft means; a plurality of housings on each of said substantially flat surfaces, spaced from each other; means between a fixed part and each housing to move the latter and retain it in its several positions; a roll housing mounted within each of said housings; a pair of rolls journaled in each roll housing; and means to actuate the rolls from the driven shafts the arrangements of the parts being such that the driven shafts and adjacent rolls are substantially parallel with each other and spaced therefrom, and the housings and rolls are supported by the respective side walls therebetween and the bottom of the bed.

5. In a tandem mill, a bed having continuous side walls, substantially parallel with and spaced from each other and a trough shaped top open at the bottom, comprising two inwardly and downwardly inclined platforms that extend substantially the length of the side walls, a plurality of roll housings, rolls within said housings, and shafts and gear means for actuating said rolls, some of said rolls, roll housings, shafts and gear means being supported upon one side of the longitudinal center of said bed by the side wall upon such side and the other of said roll housings, rolls, shafts and gear means being supported upon the opposite side of said longitudinal center by the side wall upon such side.

6. In a tandem mill, a bed having continuous side walls, substantially parallel with and spaced from each other and a trough shaped top open at the bottom, comprising two inwardly and downwardly inclined platforms that extend substantially the length of the side walls, a plurality of roll housings, rolls within said housings, and shafts and gear means for actuating said rolls, some of said rolls, roll housings, shafts and gear means being supported upon one side of the longitudinal center of said bed by the side wall upon such side and the other of said roll housings, rolls, shafts and gear means being supported upon the opposite side of said longitudinal center by the side wall upon such side.

7. In a tandem mill, a bed having continuous side walls, each of which terminates at its upper end in an inwardly and downwardly projecting platform substantially the length of the sidewalls, a plurality of roll housings movably mounted upon the top of each of said platforms and alternately projecting across the longitudinal center of the mill, rolls within said housings, and a plurality of driven shafts journaled in said platforms below the surface upon which the roll housings are mounted for actuating said rolls.

8. In a tandem mill, a bed having spaced side walls, one upon each side of the longitudinal center of the mill and each terminating at its upper end in an inwardly and downwardly projecting platform, the inner ends of the platforms being spaced from each other; a plurality of roll housings and rolls within said housings movably mounted upon the top of each of said platforms and so arranged that the upper ends thereof project over the longitudinal center of the mill and are staggered in relation to each other; and a driven shaft for each pair of rolls journaled in one of said platforms below the surface upon which the roll housings are mounted.

9. In a tandem mill, a bed having substantially solid spaced side walls extending substantially the length of the mill, one upon each side of the longitudinal center of the mill and each terminating at its upper end in an inwardly and downwardly projecting platform, the inner ends of the platforms being spaced from each other; a plurality of roll housings and rolls within said housings movably mounted upon the top of each of said platforms and so arranged that the upper ends thereof project over the longitudinal center of the mill and are staggered in relation to each other; a driven shaft for each pair of rolls journaled in one of said platforms below the surface upon which the roll housings are mounted; and means for maintaining the rolls in proper relation to each other in the housings, and actuated from that side of the mill opposite the platform upon which the roll housing is mounted.

IRVING H. TOLLES. 60
